Claims priority, application France Apr. 4, 1957
13 Claims. (Cl. 340—166)

This invention concerns selecting apparatus having electronic blocking, which is applicable notably to electronic switching.

It is known that gas diodes possess the property of becoming mutually blocked when their anode circuits are connected in parallel to a common load, as illustrated in FIGURE 1. The characteristic curve $V(I)$ of a gas diode giving the voltage existing between electrodes as a function of the current supplied by the diode is diagrammatically shown in FIGURE 2. Such a characteristic curve is divided into three parts:

A part OA in which the voltage between electrodes increases very rapidly as a function of the current supplied, as long as the firing of the tube has not taken place; the firing occurs at the point A, the ignition voltage being V_A ;

A part AB, in which, the luminous discharge having been initiated, the voltage decreases while the current increases, this being the negative-resistance portion;

A substantially horizontal part BC, in which the voltage is stabilised at V_r and regulation takes place.

If, in accordance with FIGURE 1, there exists between P and Q a voltage $V_p - V_Q$ higher than the ignition voltage V_A , and if a tube, for example the k th, is commutated to $V_p - V_Q$ by an appropriate means represented in FIGURE 1 by the switches $T_1, T_2 \dots T_k \dots T_n$, the tube fires and supplies a current I which is determined by the curve of FIGURE 2. The operating point will be at M if the loads R and r are appropriately chosen (r may be equal to zero).

If then another tube (for example the third) is switched to $V_p - V_Q$, while the k th is fired, it is clear that:

$$V_{A3} - V_{C3} = V_{A3} - V_{Q3}$$

since this tube practically does not conduct at the commutating operation, or:

$$V_{A3} - V_{Q3} = V_{Ak} - V_{Qk} = V_{Ak} - V_{Ck} + rI = V_r^*$$

Since the voltage V_r^* is lower than the firing voltage V_A , the tube of order 3 cannot fire, its operating point being at U in FIGURE 2, and the unfired diodes are blocked by the diode which is in operation.

It will be seen that the presence of the load r in the cathode-circuit has the effect of reducing the safety margin, which changes from $V_A - V_r$, in case where $r=0$, to $V_A - V_r^*$. This safety margin must be appropriately chosen if a circuit arrangement such as that of FIGURE 1 is applied to a set of tubes in which the dispersion of the characteristics will take effect.

The diodes may be replaced by thyratrons, the firing of which is effected with the aid of a third electrode, the auxiliary firing electrode, which permits of applying a lower voltage between the two anode-cathode electrodes. In the following, the auxiliary firing electrode will be called the grid. When fired, the thyratrons are blocked in a common anode circuit in the same manner as the diodes, the firing voltage at the grid of the tube first fired having previously been suppressed.

Such a method is utilised in the circuit arrangement illustrated in FIGURE 3 of the present application, which is derived from that which formed the subject of U.S. Patent 2,954,580, issued September 27, 1960, for "Elec-

2

tronic Selecting Device." The thyratrons are associated in series-parallel forming a "matrix" comprising p -lines and q -columns. The voltage V_S is applied to the grids $S_{11} \dots S_{pq}$ with the aid of switches $H_1 \dots H_p$. The voltage V_A is applied to the anodes of the thyratrons by means of switches $V_1 \dots V_q$.

In order to fire a tube such as ij in the said matrix, the following procedure is adopted:

Commutation of the voltage V_S to the grid S_{ij} by the switch H_i ,

Commutation of the voltage V_A to the anode A_{ij} by the switch V_j .

Under these conditions, the tube ij fires if the voltages V_S and V_A are appropriately chosen,

The voltage V_S is then suppressed and the voltage V_A is maintained. The tube remains in the fired condition and the regulating voltage V_r remains between the anode and the cathode.

FIGURE 4 shows the firing characteristic curve of a thyratron giving the firing voltage V_a between the anode and the cathode as a function of the voltage V_S applied to the grid. It will be seen that the characteristic curve comprises a fork defining a zone of uncertainty in regard to the firing voltage and an almost vertical portion, showing a critical grid voltage V_c , below which the tube cannot be fired, at least without reaching excessive voltages between the anode and the cathode. The voltage V_A applied between the anode and the cathode locates the commutation point, for a grid voltage V_S , at M so that the firing occurs. The grid voltage V_S being suppressed, it is known that for a tube ij :

$$V_{Aij} - V_{Cij} = V_r$$

If I is the current flowing through the tube, there will be seen in FIGURE 3:

$$V_{Aij} - V_G = V_r + rI = V_r^*$$

If r is zero, $V_r^* = V_r$.

If it is then assumed that the tube ij is in operation, and the voltage V_S is switched over the grid of the tube $2j$, for example at S_{2j} , by the switch H_2 , the voltage between the electrodes of the tube $2j$ is $V_{A2j} - V_{C2j} = V_{Aij} - V_G = V_r$, since the tube $2j$ does not conduct at the instant of the commutation. The commutation point of the tube $2j$ is therefore situated at N^* in FIGURE 4. The tube $2j$ cannot fire.

The disadvantage of this method is that it has small safety margins in view of the dispersion of the characteristic curves over a set of tubes. The firing zone accounts for a great deal of this lack of safety. It is to be noted that this zone remains if, when the tube has been extinguished, the ionic germ is created by an auxiliary anode, eliminating any external photoelectric action.

The object of the present invention is to provide a thyratron matrix having p lines and q columns which is not attended by the aforesaid disadvantages.

The present invention has for its object to provide a selecting apparatus comprising a matrix of gas tubes disposed in vertical and horizontal rows, the tubes situated in one vertical row feeding a common load, while the tubes comprise an auxiliary firing electrode, the apparatus being characterised in that the blocking of a vertical row of tubes in which a tube is fired is effected by application, to the firing electrode of the tubes of the said row, of a blocking voltage whose value is lower than the firing voltage.

In accordance with one feature of the invention, the change-over of the voltage applied to the firing electrode from the firing value to the blocking value is effected with the aid of a transistor connected in the circuit of the firing electrode.

In accordance with another feature of the invention,

a transistor is connected in the circuit of the main anode in order to effect the change-over of the control voltage of the anode.

The auxiliary firing electrode of a tube comprises a vertical control and a horizontal control for the purpose of either blocking a vertical row or blocking a horizontal row.

Further features and advantages of the invention will become apparent from the following description thereof with reference to FIGURES 5 to 7 of the accompanying drawings, which show by way of example constructional forms of the apparatus according to the invention.

FIGURE 5 is a diagram illustrating the basic principle of the apparatus according to the invention, comprising a matrix of thyatrons having *p*-lines and *q*-columns,

FIGURE 6 illustrates diagrammatically a circuit arrangement for the application of the principle according to FIGURE 5, in which the switching devices comprise transistors, and

FIGURE 7 shows diagrammatically a thyatron matrix according to the invention.

The apparatus illustrated in FIGURE 5 constitutes a matrix of thyatrons having *p*-lines and *q*-columns. The cathodes C_{11} to C_{pq} of the tubes are each connected across a resistance *r* to a common point *G* of a voltage source of negative polarity. The anodes A_{11} to A_{p1} , A_{12} to A_{p2} . . . A_{1q} to A_{pq} of tubes of one column are connected in parallel to a common load *R*, which is in turn connected to the positive terminal *F* of a voltage source V_A through a switching device diagrammatically represented in FIGURE 5 by a switch V_1 to V_q . The firing grids of the tubes are connected to a common point S_{11} to S_{pq} of two resistances *d*. The free ends of one of the resistances *d* which are situated in the same column are connected in parallel to a switching device diagrammatically represented in FIGURE 5 by a switch T_1 to T_q , of which one contact is connected to the terminal *K* of a voltage source V_h . The free end of the other resistance *d* is connected in parallel with the free end of the corresponding resistances *d* of a common line to a switching device diagrammatically represented by a changeover switch H_1 to H_p , one contact of which is connected to the terminal *H* of the voltage source V_s , while the other contact thereof is connected to the terminal *K* of the voltage source V_h .

The apparatus just described operates in the following manner:

In the state which will be called the "inoperative" state in the following, that is to say when no tube is in the fired condition, the grids of the thyatrons such as S_{ij} are at the potential of the point *K* (potential V_h). The thyatrons have a characteristic curve $V_a(V_s)$ giving the firing voltage between the anode and the cathode as a function of the grid voltage, such as that shown in FIGURE 4.

Since the matrix is assumed to be in the inoperative state, if it is desired to fire a tube, for example ij , the procedure is then as follows:

The voltage V_s is commutated to the grids of all the tubes of the line *i* by means of the reversing switch H_i . The potential of these grids is therefore then V_s .

The voltage V_A is commutated to the anodes of the column *j* by means of the switch V_j .

The tube ij is then under the conditions V_A and V_s (point *M* of FIGURE 4) and fires.

When the tube ij is supplying the current *I*, the voltage V_h is commutated to the grids of all the tubes of the column *j* by means of the switch T_j .

Under these conditions, the grid S_{ij} changes to the potential

$$\frac{V_s + V_h}{2}$$

and it will in fact be seen that:

$$V_s - V_h = 2di \text{ (mesh HS}ijK)$$

$$V_{sij} - V_h = di = \frac{V_s - V_h}{2} \quad V_{sij} = \frac{V_s + V_h}{2}$$

The voltages V_A at the anode and V_h at the grid of the column *j* are maintained and the grids of the line *i* are changed over to the voltage V_h .

The grid S_{ij} therefore returns to the potential V_h . Under these conditions, the tube ij regulates at the voltage V_r and its grid is at the voltage V_h . It will be seen that:

$$V_{Aij} - V_G = V_{Aij} - V_{Cij} + rI = V_r + rI = V_r^x$$

if V_r is the regulating voltage of the tube and *I* the current which it supplies.

The tube ij then being operative, if another line of grids, for example the line 2, is changed over to the voltage V_s , the voltage between the cathode and the anode of the tube $2j$ is:

$$V_{A2j} - V_{C2j} = V_{Aij} - V_G$$

since substantially no current is flowing in the tube at the time of the change-over from V_s , and the following is therefore deduced:

$$V_{A2j} - V_{C2j} = V_{Aij} - V_{Cij} + rI = V_r^x$$

Moreover, the grid S_{2j} is at the potential

$$\frac{V_s + V_h}{2}$$

25 Consequently, under the conditions V_r^x and

$$\frac{V_s + V_h}{2}$$

the tube $2j$ has its point of operation located at S^x in FIGURE 4. If V_s and V_h are appropriately chosen, not only will a blocking action take place at the anode circuit, but the potential of the grid will be lower than V_c .

The safety margins are increased by this double blocking. It is to be noted that the voltage V_h may be zero without necessitating any change in the foregoing reasoning.

It is further to be noted that it is possible without disadvantage to apply the voltage V_s to the grids by column in the inoperative state (which is diagrammatically illustrated in FIGURE 5 by the dash-lined connections to the switches T_1 , T_2 . . . T_j , T_q). The potentials of the grids in the inoperative state are then equal to

$$\frac{V_s + V_h}{2}$$

45 and when the voltage V_s is commutated to a grid line, the grids of the commutated line change to the potential V_s , provided that they do not belong to a column in which a tube is operative, in which case the potential changes from V_h to

$$\frac{V_s + V_h}{2}$$

55 The apparatus according to the invention permits of effecting the commutations of the grid and firing voltages without introducing any metallic contact and by using only purely electronic control means, in the present instance transistors.

In the inoperative state, the voltage V_h is continuously applied to the lines. In a preparatory phase, the voltage V_s is applied, for example, by means of a transistor and once the tube has fired, with a current flowing into the load *r*, it is possible to relay the flow of this current by any appropriate means in order to influence the transistor which has commutated the voltage V_s in order to restore the voltage V_h .

70 What is proposed to be effected by means of the present invention is the blocking of the columns of grids as soon as the tube commences to conduct by applying to the grids of the fired column the voltage V_h . In the inoperative state, the voltage V_s will be applied to the column of grids, although the potential of the grids of the inoperative matrix is

$$\frac{V_s + V_h}{2}$$

The apparatus employed for this blocking of the columns is illustrated in FIGURE 6 and comprises two transistors V_j and T_j which are connected in place of the switches V_j and T_j of FIGURE 5, a set of resistances l , m and n , and a condenser C .

There is applied to the emitter of the transistor V_j the voltage V_s , to its base the voltage V_A and to its collector the voltage $V_A - V_h$ across a resistance m . The collector of the transistor V_j is also connected to the anode A_{ij} of the tube ij across the resistance R and to the base of the transistor T_j across the resistance l . The transistor T_j comprises an emitter at the voltage V_s , a collector at the voltage V_s across the resistance n and connected to the grid of the tube ij across the resistance d , and the base of the transistor T_j is fed at the voltage $V_A - V_h$ across the resistances l and m which are connected in series and shunted by the condenser C . The letters p and q represent the multiplying points of the lines and columns of the matrix.

This apparatus operates in the following manner:

In the inoperative state, the transistor V_j , of which is at the voltage V_A , is blocked, the transistor T_j , on the other hand, discharges into the grid resistance l in series with the resistance m which permits of producing between the emitter and the base exactly the required voltage for conducting. Almost exactly the voltage V_s is transferred to the collector of the transistor T_j and the grids are therefore at:

$$\frac{V_h + V_s}{2}$$

This inoperative potential

$$\frac{V_h + V_s}{2}$$

may be brought to the value V_s if the left-hand end of the resistance d of the potential V_h is changed over to the potential V_s by any appropriate means. At this instant, if the transistor V_j is controlled through its emitter by selectively applying thereto a potential V_s it is unblocked, the voltage V_A is almost wholly transferred to the collector of V_j , and therefore to the anode circuits of the thyratrons, and the tube ij fires. This operation is due to the fact that the transistor V_j operates with its base effectively at ground potential from which follows that, when the transistor is saturated, the voltage V_A reappears substantially on the collector, the resistance between collector and base being very small under those circumstances. However, it follows from this that the base of the transistor T_j will be brought to a potential higher than V_s , since the resistance l is connected to the voltage V_A . The transistor T_j will be blocked and the voltage V_h will be transferred to its collector.

When the line is changed over to the voltage V_h , the grid S_{ij} will also be at the voltage V_h .

The function of the condenser C is to introduce a time constant into the circuit of the base of the transistor T_j in order to produce a certain delay before causing the voltage to drop at the grids on the column side. The resistances m and n are protective resistances.

The apparatus according to FIGURE 7 is a thyratron matrix according to the invention, and is formed by a combination of FIGURES 5 and 6. The matrix comprises p lines and q columns. Only the lines $1-2 \dots i$ and p with which the reversing switches $H1-H2-Hi-Hp$ are associated, and the columns 1 and j with which the transistors V_1/T_1 and V_j/T_j respectively are associated have been shown. The cathodes $C_{11}-C_{1j}-C_{1q}$ are connected in parallel to the load resistance $r1$, the other end of which is connected to the point G . Similarly, the cathodes $C_{21}-C_{2j}-C_{2q}$ of the second horizontal line are connected in parallel to the resistance $r2$, the other end of which is connected to the point G . The anodes $A_{11}-A_{1q}$ of a common vertical column are connected in parallel to the resistance $r1$, the other end of which is

connected to the collector of a transistor V_1 . Similarly, the anodes $A_{21}-A_{2j}-A_{2q}$ of the same vertical column are connected in parallel to the resistance $r2$, the other end of which is connected to the collector of the transistor V_j , etc. The grids of the tubes are each connected to the common point of two resistances d . The like free ends of the resistances d are connected together on the one hand at a common point for the horizontal line, and on the other hand at a common point for the vertical column. Thus, the grid of the tube ij is connected on the one hand through one resistance d to the centre contact of the reversing switch Hi and on the other hand through the other resistance d to the collector of the transistor T_j . The emitters of the transistors: V_1-V_j are connected respectively to appropriate devices I_1-I_j , etc., which can either connect them with the point H of voltage source V_s , or with a current injector, the bases of the same transistors being connected in parallel to the point F of potential V_A . The collector of a transistor V_j is connected to the base of the transistor T_j through a resistance l . On the other hand, the base of the transistors T_j is connected to the potential $V_A - V_h$ through the resistances l and m . The base of the transistor T_j is also connected to the potential $V_A - V_h$ through a condenser C . The collector of a transistor T_j is permanently connected to the potential V_h through a resistance n . The purpose of the resistances l , m and n and of the condenser C has been explained with reference to FIGURE 6.

The said thyratron matrix operates in the following manner:

In the inoperative state, that is to say, when no tube has fired, the transistors $V_1-V_1-V_q$ are blocked, the devices I_1 , I_{1q} connecting the emitters thereof to a potential V_s lower than the potential V_A to which the bases are connected. On the other hand, in the same inoperative state, the transistors T_1 , T_j , T_q each conduct in a circuit including the corresponding bias resistance l in series with a resistance m , which is in turn connected to a voltage source $V_A - V_h$, whereby it is possible to obtain the exact voltage necessary for conducting. Almost all the voltage V_s at the emitter is transferred to the collector, so that the grid of all the tubes are in the inoperative state at the potential

$$\frac{V_h + V_s}{2}$$

In order to effect the firing of the tube ij , the switch Hi is first changed over, the effect of which is to apply a potential V_s to one end of the grid resistance d , the other resistance already being at the potential V_s through the collector of the transistor T_j . The potential of the grid S_{ij} therefore changes from the value

$$\frac{V_h + V_s}{2}$$

to the value V_s . If a current is now injected into or a voltage is now applied to the emitter of the transistor V_j by means of the device I_j , the said transistor is unblocked and the voltage V_A is almost entirely transferred to the collector of V_j , and therefore to the anode circuits of all the thyratrons of the column j through the resistance R_j . The tube ij will therefore be fired. Moreover, the base of the transistor T_j is thus brought to a potential higher than V_s , since the resistance l connects the collector of V_j to the base of T_j , and consequently the transistor T_j will be blocked and its collector will be brought to the voltage V_h through the resistance n . On the other hand, as soon as the tube ij has been fired and has supplied a current through its cathode across the resistance $r1$, the said current produces through an appropriate device a further change-over of the reversing device Hi , which has the effect of restoring it to its initial position. Therefore, at this instant, the ends of the resistances d of the tube ij are both at the potential V_h . The grid S_{ij} is also at

the potential V_h and the tube ij operates at its regulating voltage.

The blocking of the fired tube is thus effected by the potential V_h applied to its grid. It is then no longer possible, as long as the tube ij is conducting, to fire another tube of the same column j , but it is possible to fire another tube of the same line i , the potential of the grid Sij in this case changing from the value V_h to the value

$$\frac{V_h + V_s}{2}$$

whereby complete reliability of its operation is ensured.

To sum up, in order that any tube may fire, the first condition is that the voltage V_s should be applied to the horizontal line of the grids and to the vertical column of the grids. The second condition is that the voltage V_A should be applied to the vertical column of the anodes.

The reversing switch H_i which changes over the voltage from V_h to V_s and vice versa may be of any appropriate form. It is sufficient to indicate that the voltage V_h continuously applied to the lines changes to the voltage V_s during the phase of the preparation for the firing of a tube of the corresponding line, for example by means of a transistor. Once the tube has fired, and a current is flowing across the resistance r , the flow of this current can be relayed by any appropriate means in order to influence the transistor for restoring the voltage V_h .

We claim:

1. A selecting apparatus having electronic blocking, comprising a matrix of gas tubes disposed in horizontal rows and vertical rows, each tube having a plurality of electrodes including an anode and an auxiliary firing electrode, the tubes situated in each common vertical row having their anodes connected to a common load, means including switching means for blocking a vertical row of tubes by the superposed effects of the drop of potential in the common load and by application to the auxiliary firing electrode of a blocking voltage whose value is lower than the firing voltage, a pair of resistances for each tube with the auxiliary firing electrode of the tube connected to a common point of said resistances, control means for each tube including a vertical control and a horizontal control, means for connecting one of said resistances to a respective vertical control and means for connecting the other resistance to a respective horizontal control, means for selectively connecting each one of said controls independently one from the other either to a firing voltage or to a blocking voltage, means for applying the anode voltage including a further vertical control, the firing voltage being applied, at rest, to the auxiliary electrode by way of the vertical control, the same firing voltage being applied, in operation, by way of the horizontal control so that a tube is fired by setting into position of operation the horizontal and vertical controls, the output itself of said tube automatically setting the horizontal control in its initial position of rest, and the placing into operation of the vertical control automatically causing the switching of the vertical control into the blocking position thereof, the effect of these automatic switchings after firing of the tube resulting in the blocking in the rest position of the tubes of the same vertical row as the fired tube and the blocking of the fired tube in its operative state.

2. A selecting apparatus according to claim 1, wherein said horizontal and vertical controls each include a commutation device, and further comprising means for applying a bias to the end of one of the resistances by means of the commutation device for the horizontal control and means for applying a bias to the other end of the other resistance by means of the commutation device for the vertical control.

3. A selecting apparatus according to claim 1 wherein for said one tube the commutation of the voltage of the

auxiliary firing electrode and of the voltage of the anode is effected with the aid of a transistor, so as to block the firing electrodes of the other tubes in a respective row as soon as said one tube commences to conduct, a first transistor being connected in the circuit of the firing electrode to effect the change-over of the bias at the firing electrode from the blocking value to the firing value and then to the blocking value and a second transistor being connected in the circuit of the anode to effect the change-over of the control voltage of the anode.

4. A selecting apparatus according to claim 1 wherein there is associated with each vertical row a set of two transistors, the first of which simultaneously controls the change-over of the anode voltage for each tube of said vertical row and the blocking or unblocking of the second

transistor, the latter successively applying to the auxiliary firing electrode of each tube of said vertical row the firing voltage when the second transistor conducts and the blocking voltage when it is blocked.

5. A selecting apparatus according to claim 4, wherein the collector of the second transistor is connected to the auxiliary firing electrode for its vertical control, the base of this transistor being connected across a resistance to the collector of the first transistor, said collector of the first transistor also being connected to the anode of each of the tubes of the respective vertical row, biases being applied to the bases and to the collectors of the transistors and control currents being applied to the emitters, so that when the first transistor is blocked the second conducts and when the first transistor conducts the second is blocked.

6. A selecting apparatus according to claim 4, wherein the base of the second transistor is connected to a particular voltage through a resistance, a condenser being provided to shunt the resistance in such manner that the blocking commutation of the firing electrode is slightly staggered in relation to the application of voltage to the anode.

7. In a selecting apparatus having a matrix of gaseous discharge tubes disposed in horizontal and vertical rows each tube being provided with a plurality of electrodes including two main electrodes and an auxiliary firing electrode, the tubes situated in each common vertical row having one of their respective main electrodes connected to a common load circuit, and the tubes situated in a common horizontal row having their respective grids each connected to two respective resistance elements, the free ends of one of each of the two resistance elements of each tube in a respective common horizontal row being connected together into a first common energizing circuit and the free ends of the other one of each of the two resistance elements of each tube in a respective common vertical row being connected together in a second energizing circuit, the improvement essentially consisting of switching means to enable selective firing of only one gaseous discharge tube in each vertical row while enabling selective firing of a gaseous discharge tube disposed in the same horizontal row as said last-mentioned one tube, comprising a first switching means for each vertical row operatively connected to a respective common load circuit for normally applying a voltage to said one main electrodes of each tube disposed in said vertical row which is insufficient to enable firing of any of the tubes in said vertical row, a second switching means for each horizontal row to selectively apply to each of said other free ends of the respective resistance elements of said horizontal row two voltages of different value, a third switching means for each vertical row operatively connected with the free ends of said one resistance elements of the tubes disposed in said respective vertical row for selectively applying one of two voltages to said one resistance elements, said first, second and third switching means each having two operating states, selecting means for selectively firing one of said tubes including first means operatively connected with said first switching means for selectively switching a preselected one of said first switching means from one state to the other state and

second means operatively connected with said second switching means for selectively switching a preselected one of said second switching means from one state to the other state, connecting means operatively connecting a first switching means with a third switching means belonging to a respective vertical row to selectively switch the respective third switching means from its pre-existing state to the other upon switching of the corresponding first switching means by a respective first means.

8. In a selecting apparatus having a matrix of gaseous discharge tubes disposed in horizontal and vertical rows, each tube being provided with a plurality of electrodes including two main electrodes and an auxiliary firing electrode, the tubes situated in each common vertical row having one of their respective main electrodes connected to a common load circuit, and the tubes situated in a common horizontal row having their respective grids each connected to two respective resistance elements, the free ends of one of each of the two resistance elements of each tube in a respective common horizontal row being connected together into a first common energizing circuit and the free ends of the other one of each of the two resistance elements of each tube in a respective common vertical row being connected together in a second energizing circuit, the improvement essentially consisting of electronic switching means to enable selective firing of only one gaseous discharge tube in each vertical row while enabling selective firing of a gaseous discharge tube disposed in the same horizontal row as said last-mentioned one tube, comprising a first transistorized switching means for each vertical row operatively connected to a respective common load circuit for normally applying a voltage to said one main electrodes of each tube disposed in said vertical row which is insufficient to enable firing of any of the tubes in said vertical row, a second switching means for each horizontal row to selectively apply to each of said other free ends of the respective resistance elements of said horizontal row two voltages of different value a third transistorized switching means for each vertical row operatively connected with the free ends of said one resistance elements of the tubes disposed in said respective vertical row for selectively applying one of two voltages to said one resistance elements, said first, second and third switching means each having two operating states, selecting means for selectively firing one of said tubes including first means operatively connected with said first transistorized switching means for selectively switching a preselected one of said first switching means from one state to the other state and second means operatively connected with said second switching means for selectively switching a preselected one of said second switching means from one state to the other state, connecting means operatively connecting a first switching means with a third switching means belonging to a respective vertical row to selectively switch the respective third switching means from its pre-existing state to the other upon switching of the corresponding first switching means by a respective first means, and current responsive means operatively associated with a respective tube for returning the respective second switch means belonging to the horizontal row in which the fired tube is disposed to its pre-existing state and thereby blocking said fired tube.

9. A selecting apparatus comprising a matrix of gaseous discharge tubes disposed in horizontal and vertical rows, each tube being provided with a plurality of electrodes including two main electrodes connected in a discharge circuit and an auxiliary firing electrode, the tubes situated in each common vertical row having one of their respective main electrodes connected to a common load circuit, and the tubes situated in a common horizontal row having their respective grids connected each to two resistance elements, first circuit means operatively connected to all the free ends of one of the two resistance elements associated with the grids of the tubes in a respec-

tive horizontal row, second circuit means operatively connected to all the free ends of the other of the two resistance elements associated with the grids of the tubes in a respective vertical row, first switch means in each first circuit means for selectively applying thereto, on the one hand, a first voltage which prevents firing of any tubes in the corresponding horizontal row and, on the other, a second voltage which enables firing of a preselected one of the tubes thereof, second switch means in each common load circuit for selectively applying to the one main electrode of the tubes in a corresponding vertical row a firing voltage enabling firing of the tube to the grid resistance element of which is also applied said second voltage by a respective first switch means, third switch means in each second circuit means for selectively applying thereto on the one hand, a first voltage which enables firing of a tube associated with its circuit upon application to its grid circuit of said second voltage by said first switch means and, on the other, a second voltage which effectively provides a blocking voltage at the grid of a tube associated with its circuit, to the grid circuit of which is also applied said first voltage by a corresponding first switch means, means operatively connected with the discharge circuit of a respective tube for changing the first switch means associated therewith to apply to a corresponding first circuit means said first voltage upon firing of said tube, first control means for selectively energizing a preselected second switch means, second control means for selectively changing a preselected first switch means to apply to a corresponding first circuit means said second voltage, and connecting means operatively connecting the second switch means with the third switch means of a respective vertical row to change the associated third switching means to apply to said second circuit means said second voltage upon energization of the corresponding second switch means by said first control means to thereby effectively provide a blocking voltage at the grid of each tube in the vertical row associated with said third switch means.

10. A selecting apparatus comprising a matrix of gaseous discharge tubes disposed in horizontal and vertical rows, each tube being provided with a plurality of electrodes including two main electrodes connected in a discharge circuit and an auxiliary firing electrode, the tubes situated in each common vertical row having one of their respective main electrodes connected to a common load circuit, and the tubes situated in a common horizontal row having their respective grids connected each to two resistance elements, first circuit means operatively connected to all the free ends of one of the two resistance elements associated with the grids of the tubes in a respective horizontal row, second circuit means operatively connected to all the free ends of the other of the two resistance elements associated with the grids of the tubes in a respective vertical row, first switch means in each first circuit means for selectively applying thereto, on the one hand, a first voltage which prevents firing of any tubes in the corresponding horizontal row and, on the other, a second voltage which enables firing of a preselected one of the tubes thereof, second switch means including a transistor in each common load circuit for selectively applying to the one main electrode of the tubes in a corresponding vertical row a firing voltage enabling firing of the tube to the grid resistance element of which is also applied said second voltage by a respective first switch means, third switch means including a transistor in each second circuit means for selectively applying thereto on the one hand, a first voltage which enables firing of a tube associated with its circuit upon application to its grid circuit of said second voltage by said first switch means and upon application to the one main electrode thereof of said firing voltage by said second switch means and, on the other, a second voltage which effectively provides a blocking voltage at the grid of a tube associated with its circuit, to the grid circuit of which is also applied said first voltage by a corresponding first switch means, means

operatively connected with the discharge circuit of a respective tube for changing the first switch means associated therewith to apply to a corresponding first circuit means said first voltage upon firing of said tube, first control means for selectively energizing a preselected second switch means, second control means for selectively changing a preselected first switch means to apply to a corresponding first circuit means said second voltage, and connecting means operatively connecting the second switch means with the third switch means of a respective vertical row to change the associated third switching means to apply to said second circuit means said second voltage upon energization of the corresponding second switch means by said first control means to thereby effectively provide a blocking voltage at the grid of each tube in the vertical row associated with said third switch means, each transistor including a base, a collector and an emitter, and said connecting means operatively connecting the collector of the transistor in said second switch means with the base of the transistor in said third switch means.

11. A selecting apparatus comprising a matrix of gaseous discharge tubes disposed in horizontal and vertical rows, each tube being provided with a plurality of electrodes including two main electrodes connected in a discharge circuit and an auxiliary firing electrode, the tubes situated in each common vertical row having one of their respective main electrodes connected to a common load circuit, and the tubes situated in a common horizontal row having their respective grids connected each to two resistance elements, first circuit means operatively connected to all the free ends of one of the two resistance elements associated with the grids of the tubes in a respective horizontal row, second circuit means operatively connected to all the free ends of the other of the two resistance elements associated with the grids of the tubes in a respective vertical row, first switch means in each first circuit means for selectively applying thereto, on the one hand, a first voltage which prevents firing of any tubes in the corresponding horizontal row and, on the other, a second voltage which enables firing of a pre-selected one of the tubes thereof, second switch means including a transistor in each common load circuit for selectively applying to the one main electrode of the tubes in a corresponding vertical row a firing voltage enabling firing of the tube to the grid resistance element of which is also applied said second voltage by a respective first switch means, third switch means including a transistor in each second circuit means for selectively applying thereto on the one hand, a first voltage which enables firing of a tube associated with its circuit upon application to its grid circuit of said second voltage by said first switch means and upon application to the one main electrode thereof of said firing voltage by said second switch means and, on the other, a second voltage which effectively provides a blocking voltage at the grid of a tube associated with its circuit, to the grid circuit of which is also applied said first voltage by a corresponding first switch means, means operatively connected with the discharge circuit of a respective tube for changing the first switch means associated therewith to apply to a corresponding first circuit means said first voltage upon firing of said tube, first control means for selectively energizing a preselected second switch means, second control means for selectively changing a preselected first switch means to apply to a corresponding first circuit means said second voltage, and connecting means operatively connecting the second switch means with the third switch means of a respective vertical row to change the associated third switching means to apply to said second circuit means said second voltage upon energization of the corresponding second switch means by said first control means to thereby effectively provide a blocking voltage at the grid of each tube in the vertical row associated with said third switch means, each transistor including a base, a collector and an emitter, each transistor of said second switch means being nor-

mally non-conducting and each transistor of said third switch means being normally conducting, and said connecting means operatively connecting the collector of the transistor in said second switch means with the base of the transistor in said third switch means in such a manner that upon actuation of a respective control means the transistor of the second switch means is rendered conductive and the transistor of the third means is rendered non-conductive.

10. 12. In a selecting apparatus having a matrix of gaseous discharge tubes disposed in horizontal and vertical rows, each tube being provided with a plurality of electrodes including two main electrodes and an auxiliary firing electrode, the tubes situated in each common vertical row having one of their respective main electrodes connected to a common load circuit, and the tubes situated in a common horizontal row having their respective grids each connected to two respective resistance elements, the free ends of one of each of the two resistance elements of each tube in a respective common horizontal row being connected together into a first common energizing circuit and the free ends of the other one of each of the two resistance elements of each tube in a respective common vertical row being connected together in a second energizing circuit, the improvement essentially consisting of switching means to enable selective firing of only one gaseous discharge tube in each vertical row while enabling selective firing of a gaseous discharge tube disposed in the same horizontal row as said last-mentioned one tube, comprising a first switching means for each vertical row operatively connected to a respective common load circuit for normally applying a voltage to said one main electrodes of each tube disposed in said vertical row which is insufficient to enable firing of any of the tubes in said vertical row, a second switching means for each horizontal row to selectively apply to each of said other free ends of the respective resistance elements of said horizontal row two voltages of different value, a third switching means for each vertical row operatively connected with the free ends of said one resistance elements of the tubes disposed in said respective vertical row for selectively applying one of two voltages to said one resistance elements, said first, second and third switching means each having two operating states, selecting means for selectively firing one of said tubes including first means operatively connected with said first switching means for selectively switching a preselected one of said first switching means from one state to the other state and second means operatively connected with said second switching means for selectively switching a preselected one of said second switching means from one state to the other state, connecting means operatively connecting a first switching means with a third switching means belonging to a respective vertical row to selectively switch means the respective third switching means from its pre-existing state to the other upon switching of the corresponding first switching means by a respective first means, and current responsive means operatively associated with a respective tube for returning the respective second switch means belonging to the horizontal row in which the fired tube is disposed to its pre-existing state and thereby blocking said fired tube.
13. In a selecting apparatus having a matrix of gaseous discharge tubes disposed in horizontal and vertical rows, each tube being provided with a plurality of electrodes including two main electrodes and an auxiliary firing electrode, the tubes situated in each common vertical row having one of their respective main electrodes connected to a common load circuit, and the tubes situated in a common horizontal row having their respective grids each connected to two respective resistance elements, the free ends of one of each of the two resistance elements of each tube in a respective common horizontal row being connected together into a first common energizing circuit and the free ends of the other one of

each of the two resistance elements of each tube in a respective common vertical row being connected together in a second energizing circuit, the improvement essentially consisting of electronic switching means to enable selective firing of only one gaseous discharge tube in each vertical row while enabling selective firing of a gaseous discharge tube disposed in the same horizontal row as said last-mentioned one tube, comprising a first transistorized switching means for each vertical row operatively connected to a respective common load circuit for normally applying a voltage to said one main electrode of each tube disposed in said vertical row which is insufficient to enable firing of any of the tubes in said vertical row, a second switching means for each horizontal row to selectively apply to each of said other free ends of the respective resistance elements of said horizontal row two voltages of different value, a third transistorized switching means for each vertical row operatively connected with the free ends of said one resistance elements of the tubes disposed in said respective vertical row for selectively applying one of two voltages to said one resistance elements, said first, second and third switching means each having two operating states, selecting means for selectively firing one of said tubes including first means operatively connected with said first transistorized switching means for selectively switching a preselected one of said first switching means from one state to the other state and second means operatively connected with said second switching means for selectively switching a

preselected one of said second switching means for one state to the other state, connecting means operatively connecting a first switching means with a third switching means belonging to a respective vertical row to selectively switch the respective third switching means from its pre-existing state to the other upon switching of the corresponding first switching means by a respective first means.
